J. LUTTMANN.

TRUNK LOCK.

APPLICATION FILED JAN. 7, 1921.

1,417,264.

Patented May 23, 1922.

UNITED STATES PATENT OFFICE.

JOSEPH LUTTMANN, OF CINCINNATI, OHIO, ASSIGNOR TO THE MENDEL-DRUCKER COMPANY, OF CINCINNATI, OHIO, A CORPORATION OF OHIO.

TRUNK LOCK.

1,417,264.

Specification of Letters Patent. Patented May 23, 1922.

Application filed January 7, 1921. Serial No. 435,732.

To all whom it may concern:

Be it known that I, JOSEPH LUTTMANN, a citizen of the United States of America, and resident of Cincinnati, in the county of 5 Hamilton and State of Ohio, have invented a new and useful Improvement in Trunk Locks, of which the following is a specification.

An object of my invention is to provide a 10 locking device for trunks and the like in which the strain of securing the lid thereon is not directed upon the locking member itself.

Another object is to provide a positive 15 locking means operative at several places on a trunk at the same time.

These and other objects are attained by the means described herein and disclosed in the accompanying drawing in which:

20 Fig. 1 is a fragmental front elevation of a trunk having mounted upon it a locking device embodying my invention.

Fig. 2 is an enlarged sectional view on line 2—2 of Fig. 1.

25 Fig. 3 is an enlarged fragmental view of the interior of the trunk shown in Fig. 1.

My invention comprises a series of hooks adapted to secure the lid upon the body of the trunk, a reciprocating rod adapted to 30 actuate the hooks, a hasp adapted to control the rod and provided with means whereby it may be locked against movement.

The trunk A has mounted on its body a, the revoluble pin a' extending through the body a and through the plates a² and a³ mounted upon the exterior and interior respectively of the body by any suitable means such as rivets a⁴. Mounted upon the exterior of the pin is the plate a⁵, secured 35 thereupon by any suitable means such as being mounted by means of rivets a⁴ upon the flange a⁶ formed on the pin. A hasp a⁷ is pivotally mounted on the plate and has mounted upon it a suitable lock a⁸ such as 40 is ordinarily employed with trunks, the hasp being adapted to be moved adjacent the lid a⁹ so that the lock may engage the catch a⁹ on the lid and secure the plate against rotatory motion. Interiorly of the trunk the 45 pin a' has a square head a¹⁰ formed upon it and upon such head is mounted the hook a¹¹. The hook a¹¹ is adapted to engage the stud a¹² mounted on the lid a⁹ and thereby

55 prevents raising of the lid. A series of supplemental hooks a¹³ are pivotally mounted within the trunk and upon the pivots a¹⁴ and each hook is adapted to engage a stud a¹² mounted upon the interior of the lid a⁹. A rod a¹⁵ is pivotally mounted upon pins a¹⁶ mounted on the hooks and is adapted to 60 transmit rotatory motion from the main hook a¹² to the supplemental hooks a¹³.

The operation of my device is as follows:

We will assume the trunk is closed and locked. To open the trunk, the key a¹⁸ is 65 inserted in the lock a⁷ so as to release the lock a⁷, hasp a⁷ and plate a⁵ from the catch a⁹ on the lid a⁹. The hasp is then revolved thereby turning the pin a' and revolving the hook a¹¹ and withdrawing the hook from 70 engagement with the pin a¹² on the lid. The motion of the hook a¹¹ is transmitted to the supplemental hooks a¹³ by means of the rod a¹⁵, whereby the supplemental hooks are disengaged from the pins a¹² on the lid. To 75 lock the trunk the procedure is reversed.

What I claim is:—

1. In a trunk locking device the combination of a revoluble pin mounted upon and extending through one relatively movable 80 member of a trunk, a hasp mounted fixedly upon the pin exteriorly to the trunk, means to lock the hasp against rotatory motion, a stud mounted on the interior of the cooperating movable member of the trunk, and 85 a hook mounted on the pin interiorly of the trunk and adapted to engage the stud when the hasp is locked against motion.

2. In a trunk locking device the combination of a revoluble pin mounted upon and 90 extending through one relatively movable member of a trunk, a hasp mounted fixedly upon the pin exteriorly to the trunk, means to lock the hasp against rotatory motion, studs mounted on the interior of the cooperating movable member of the trunk, a hook fixedly mounted on the pin interiorly to the trunk, a second hook mounted revolvably upon the interior of the first mentioned trunk member, each hook being adapted to 95 engage a stud, and a rod pivotally connecting the hooks.

3. In a trunk locking device the combination of a revoluble pin mounted upon and extending through one relatively movable 105 member of a trunk, a hasp mounted fixedly

upon the pin exteriorly of the trunk, means to lock the hasp against rotatory motion, a hook mounted fixedly upon the pin interiorly of the trunk, a second hook mounted pivotally upon the interior of the trunk, studs mounted on the interior of the cooperating movable means of the trunk adapted to be

engaged by the hooks, pins on the hooks and a rod pivotally connecting the pins on the hooks.

10

In testimony whereof, I have hereunto subscribed my name this 4th day of January, 1921.

JOSEPH LUTTMANN.
